J. H. OWENS

PIT COVER

Filed Sept. 21 1927

Inventor.

John Henry Owens,
Rummel & Rummel,

Atty's:

Witness
Tom E. Anderson.

UNITED STATES PATENT OFFICE.

JOHN HENRY OWENS, OF ELGIN, ILLINOIS.

PIT COVER.

Application filed September 21, 1927. Serial No. 220,983.

The main objects of this invention are to provide an improved form of cover which is particularly adapted for use in connection with pits; to provide improved means for hinging and anchoring the cover to the walls of the pit; to provide improved means in the mouth of the pit for supporting the cover; and to provide supporting means of this kind which are removable to permit ready access to the pit when the cover is open.

An illustrative embodiment of this invention is shown in the accompanying drawing, wherein:

15 Fig. 1 is a plan of a pit and cover to which this invention is applied, part of one of the cover sections being broken away.

Fig. 2 is a vertical section, taken on the line 2—2 of Fig. 1.

20 Fig. 3 is a transverse section, taken on the line 3—3 of Fig. 1.

Fig. 4 is a detail in section, taken on the line 4—4 of Fig. 1; the dotted outline representing a door section in partly open position.

25 Manholes heretofore in use by public utilities in connection with gas and water mains, and other underground service lines, consisted of pits of considerable size having roofs provided with contracted openings through which the workmen passed in entering and leaving the pit. Such pits were made sufficiently deep to enable the workmen to stand erect in them. Due to the 30 large dimensions of those pits, a large amount of concrete or other building material was necessary in constructing the walls and roof, which made the construction of a pit very costly.

35 40 The deep pits heretofore in use were objectionable also from the standpoint of sanitation, because the pit floor was frequently located below the level of the street sewer, making it impossible to drain the waste material, which usually enters street pits.

45 The deep type of pit heretofore in use in connection with gas mains has resulted in the asphyxiation of many workmen who, when overcome by escaping gas, were unable to climb out of the pit through the contracted opening in the roof.

50 The aforementioned objections to the pits heretofore in use have been cured by the im-

proved pits to which this invention is applied. In the embodiment herein shown, the invention is applied to a comparatively shallow open pit having an improved form of cover which spans the entire pit so as to avoid the necessity of the objectionable roof constructions heretofore in use. The cover is supported by an improved beam structure which is removable to permit ready access to the pit when the cover is open.

In the form shown, the public utility manhole to which this invention is applied comprises an open governor pit 1 having a plurality of removable beams 2 spanning its open end for supporting a hinged cover 3.

The pit 1 is preferably made of concrete and comprises a bottom 4 and upright side walls 5 and end walls 6. The bottom 4 is provided with the customary drain 7. Formed in the side walls 5, are openings 8, through which a gas main 9 extends. The usual governor, not shown, is connected to the main 9 and is located within the pit. Formed in the upper edges of the walls 5, are recesses 10 providing seats for the side edges of the cover 3.

Formed in the end walls 6, adjacent the upper edges thereof, are recesses 11, having liners 12 forming seats for the removable beams 2. The liners 12 are preferably sheet metal and comprise side plates 13, which are welded or otherwise secured to base plates 14 anchored in the concrete walls.

The beams 2 may be of any form but are preferably structural steel I-beams of sufficient length to span the pit so as to be adapted to rest in the liners 12. Three beams are shown in the drawing, but any desired number may be used. One of the beams is arranged so as to support substantially the center of the cover and the other beams are arranged on opposite sides of the center beam.

In the form shown, the cover 3 comprises two sections 15 which are hinged to one of the end walls 6 and two other sections 16 which are hinged to the opposite end wall. 100 These cover sections 15 and 16 are preferably metal plates of sufficient strength to bear the street traffic which passes over them. Rigidly secured to the cover sections 15 and 16, are hinge members 17, which are connected to a hinge pin 18 mounted on a plurality of

anchors 19 embedded in the walls 6. The upper edges of the end walls 6 are preferably recessed so as to permit the hinges and the cover sections to lie flush with the rim of the pit.

Mounted on the lower faces of the sections 15 are depending brackets 20, which support locking bolts 21, which are slidable into engagement with the lower face of the center beam 2 for locking the cover. Formed in the cover sections 15, are apertures 22, through which a tool, not shown, may be inserted for engagement with lugs 23 on the locking bolts 21, whereby the bolts may be shifted into and out of locking position. The cover sections 16 are provided with tongues 24 adapted to engage the lower faces of the sections 15 to secure the sections 16 against opening while the sections 15 are closed.

With this improved form and arrangement of parts, the pit may be made comparatively shallow so that workmen standing in the pit may have their heads above ground, thereby eliminating the danger of asphyxiation. To enter the pit, the cover sections 15 are unlocked and opened before opening the sections 16. After the cover is opened, the beams 2 are lifted from their seats so as to leave the entire top of the pit open.

Although but one specific embodiment of this invention has been herein shown and described, it will be understood that numerous details of the construction shown may be altered or omitted without departing from

the spirit of this invention as defined by the following claims.

I claim:

1. A public utility manhole comprising an open pit having upright walls provided with recesses in the upper edges thereof, a structural steel beam removably seated in said recesses and spanning the pit, a hinge pin anchored to one of said walls, and a cover mounted on said pin and loosely supported on said beam.

2. A public utility manhole comprising an open pit having upright concrete walls provided with recesses in the upper edges thereof, structural steel beams removably seated in said recesses and spanning the pit, a pair of hinge pins anchored to respectively opposite walls of the pit, and a plurality of cover sections connected to said hinge pins and loosely supported on said beams.

3. A public utility manhole comprising an open pit having upright concrete walls provided with recesses in the upper edges thereof, structural steel beams removably seated in said recesses and spanning the pit, a pair of hinge pins anchored to respectively opposite walls of the pit, a plurality of cover sections connected to said hinge pins and loosely supported on said beams, and means for locking said cover sections to one of said beams.

Signed at Aurora, Illinois, this 16th day of September, 1927.

JOHN HENRY OWENS.
